UNITED STATES PATENT OFFICE.

JOHN JARRETT, OF PITTSBURG, JOHN R. DAVIES, OF DUQUESNE, AND JOHN EDWARDS, OF HOMESTEAD, PENNSYLVANIA.

CAR-COUPLING.

SPECIFICATION forming part of Letters Patent No. 591,257, dated October 5, 1897.

Application filed January 18, 1897. Serial No. 619,535. (No model.)

To all whom it may concern:

Be it known that we, JOHN JARRETT, of Pittsburgh, JOHN R. DAVIES, of Duquesne, and JOHN EDWARDS, of Homestead, in the county of Allegheny and State of Pennsylvania, have invented a new and useful Improvement in Car-Couplers, of which the following is a full, clear, and exact description, reference being had to the accompanying drawings, forming part of this specification, in which—

Figure 1 is a horizontal section of two cars provided with our improved coupling. Fig. 2 is a partial end elevation of a car with our coupler and operating-rod attached. Fig. 3 is a bottom plan view, partly broken away. Fig. 4 is a side elevation of one of the couplers, and Fig. 5 is a longitudinal section showing the couplers locked together.

Our invention relates to that class of car-couplers wherein twin jaws are employed, each jaw having upon one side a swinging hook or knuckle and upon the other side a rigid hook portion which is engaged by the knuckle of the opposite head; and it is designed to enable couplers of this class to couple together where the heads are out of register with each other either vertically or laterally.

In the drawings, in which similar numerals indicate corresponding parts, 2 represents the coupler-head, which is preferably provided on its front face with a reversely-curved or S-shaped surface, as shown. The rear portion of the head is provided with two recesses having curved inner faces 3, in which recesses fit the lugs 4 of the draw-bar, a pivot-pin 5 passing down through the coupler and the draw-head lugs, the inner ends of the lugs being curved correspondingly to the curvature of the inner faces of the recesses. The pin is reduced in diameter at the point 6, so as to provide a shoulder which rests upon the lower face of the coupler-recess and prevents dropping of the pin in case it should be broken below its head. A pivotal connection is thus given between the coupler-head and the draw-bar, which connection is of great strength and security on account of the several interfitting lugs and the fact that the pin, though broken in two or more parts, will still remain in position and hold the

parts in place. Upon one side the coupler-head is provided with two projecting lugs 7, which fit within recesses in a swinging knuckle 8, having a hooked head 9, and a lower projecting tailpiece 10. Through a slot 11 in the tailpiece passes a headed pin 12, which passes through a guiding-hole in a lug 13, projecting downwardly from the coupler-head, a spiral spring 14 being interposed between the lug upon the coupler-head and the tail of the knuckle, so as to normally throw the knuckle-hook inwardly. Each coupler-head is provided on the side opposite to that of the knuckle with a rigid hook portion 15, adapted to be engaged by the knuckle of the opposite coupler-head when the couplers engage each other. The pin 16, which forms the pivot for the knuckle, is shown formed with a reduced portion 17, in the same manner and for the same purpose as the pivot-pin for the coupler-head. The knuckles are disengaged from their coupled positions by chains 18, secured to the end of the knuckle-tail and extending sidewise and upwardly, as shown in Fig. 2, to a lever 19, secured to a rod 20. The rod 20 is provided with handles 21 at each end, and is rotatably mounted in bearings 22, through which it may be slid longitudinally. It is evident that when this rod is rotated the chain acting upon the tail of the knuckle will swing the same open, after which the rod may be slid longitudinally, so as to bring the lever 19 in its lifted position behind a lug or bracket 23, secured to the end of the car, thus holding the knuckle in unlocked position. The coupler-heads may be slotted, as shown at 24, if desired, and provided with vertical holes 25, by means of which either coupler-head may be united to a coupler of a different type by the ordinary link-and-pin connection.

The operation of the coupler will be apparent to those skilled in the art, the heads of the knuckles riding over the curved end portions of the coupler-head and the springs throwing them inwardly, so as to engage the coupler-head hook as the coupler-heads come together, the uncoupling being performed by operating the rods 20 to disengage the knuckles, as above described. The pins 5 and 16 may be formed without the reduced portions

6 and 17, in which case the lower lug of the 5
coupler-head or draw-bar is provided with a
socket of the diameter of the pin, a smaller
hole extending through the lug to permit the
insertion of a rod to remove the pin, as in case
of breakage of the pin.

The advantages of our invention are nu- 10
merous. The knuckle engaging a portion of
the opposite coupling - head, the pulling-
strain does not tend to disengage the knuc-
kle, but rather to hold it more firmly in
position. The engagement of the hooks being
15 on the opposite sides of the heads, the strain
is equally distributed on both sides of the
coupling. The coupler-heads being pivoted
to the draw-bar, a coupling may be effected
on any curve. The connections between the
coupler-head and the draw-bar and between
20 the coupler-head and knuckle being in the
form of several interfitting lugs, one or more
of these lugs may be broken, or the pin may
be broken, without materially interfering
with the operation of the coupler. The shock
25 of impact when the cars meet is borne by the
coupler-head and draw-bar and danger of
breaking the knuckle is greatly lessened.
The knuckles being held in engaging position
by yielding pressure rather than by a positive
30 lock, in case of an accident the overturning
of one car will force back the knuckles and
uncouple the cars. The parts of the coup-
ling are very simple and few in number and
are not liable to get out of order by breakage
35 or action of ice, &c. By making the coupler-
head separate from the draw-bar in the event
of breakage of either it is unnecessary to re-
new anything but the broken portion.

We prefer to make the spiral spring 14 in
40 double form, one spring lying within the
coils of the other, so that if one spring should
break the other will perform the necessary
functions. The form of the coupler-head,
the knuckles, &c., may be varied without de-
parting from our invention, since

45 We claim—

1. A coupler provided with a front face hav-
ing a concave and convex portion, these por-
tions merging into each other, said coupler
having on one side a swinging knuckle, and
50 on the other side a rigid hook portion ar-
ranged to be engaged by the knuckle of the
opposite coupler.

2. A pivotally-mounted coupler-head, pro-
vided with a front face having a concave and
convex portion, these portions merging into 55
each other, said head having at one side a
swinging knuckle and at the other a rigid
hook portion arranged to be engaged by the
knuckle of the opposite coupler-head.

3. A pivotally-mounted coupler-head pro- 60
vided with a front face having a concave and
convex portion, these portions merging into
each other, said head having pivoted to one
side thereof a swinging knuckle, a spring
arranged to force the knuckle normally in 65
wardly, and a rigid hook portion upon the
other side of the head arranged to be engaged
by the knuckle of the opposite coupler-head.

4. A coupler - head having a front face
which is provided with a transverse concave 70
portion merging into a convex portion, a
swinging knuckle pivoted at one side of the
coupler-head, a rigid hook portion at the other
side of the coupler-head arranged to be en-
gaged by the knuckle of the opposite coup- 75
ler-head, and a draw-bar having a pivotal
connection with the coupler-head.

5. A coupler-head having a pivotal connec-
tion with a draw-bar, said connection con-
sisting of interfitting lugs, and a pivot-pin 80
passing therethrough, a swinging knuckle
having a similar pivotal connection to the
coupler-head, and a rigid hook upon the other
side of the coupler-head.

6. A coupler-head having a front face pro- 85
vided with a concave and convex portion,
these portions merging into each other, a
rigid hook at one side thereof, a swinging
knuckle pivoted at the other side, and having
a tailpiece, a spring arranged to normally 90
throw the knuckle inwardly, and a chain con-
nected to the tailpiece.

In testimony whereof we have hereunto set
our hands.
